Primary Examiner—Ian Simmons
Assistant Examiner—Maurice Stevens(74) *Attorney, Agent, or Firm*—Finnegan, Henderson, Farabow, Garrett & Dunner, L.L.P.(57) **CLAIM**

The ornamental design for the airship, as shown and described.

DESCRIPTION

FIG. 1 is a lower right perspective view of an airship of my new design;

FIG. 2 is the top view thereof;

FIG. 3 is the bottom view thereof;

FIG. 4 is a front view thereof;

FIG. 5 is a rear view thereof;

FIG. 6 is a right side view thereof;

FIG. 7 is a left side view thereof; and,

FIG. 8 is a close up perspective view of the gondola portion of the airship.

The elements of the airship depicted in broken lines form no part of the claimed design.
